UNITED STATES PATENT OFFICE

2,446,490

METHOD OF PRODUCING CONNECTOR BARS

Wayne R. Scherer, Trooper, Pa., assignor to Taylor Fibre Company, Norristown, Pa., a corporation of Pennsylvania

Application June 1, 1944, Serial No. 538,222

3 Claims. (Cl. 154—117)

1

This invention relates to an improvement in the method of producing connector bars.

Connector bars are provided in circuit breakers, which find various uses, as, for example, in switch mechanism; and, mounted for rotation, carry contacts for the making and breaking of circuits.

As is well known, contact bars have heretofore been formed from metal, as steel, and of substantial size, since they are subjected to considerable torque. The metal bar is covered with an insulating material, as fabric or paper, impregnated with a synthetic resinous material, as a phenol formaldehyde resin, which is molded to the contour of the bar, which is usually four sided. The contacts are clamped to the bar outside of the insulating covering, which extends somewhat beyond the end of the bar to enable the ends to be sealed with insulating material.

Contact bars as heretofore made have been open to various objection in that no means are provided to insure against endwise movement of the metal bar in the insulating covering, beyond the frictional engagement of the covering with the bar; and their production has only been accomplished by separately wrapping the bars.

Now in accordance with this invention from the product standpoint, a contact bar, of the type indicated, is provided of such construction that the metal bar is positively held against endwise movement; while from the method standpoint procedure is provided whereby a plurality of the bars of the novel construction may be wrapped simultaneously with accuracy and dispatch.

Having now indicated, in a general way, the nature and purpose of this invention, I will proceed to a detailed description of a preferred procedure for the production thereof, all with reference to the accompanying drawing in which:

Figure 1 is a side view of a plurality of contact bars assembled for wrapping with insulating material.

Figure 2 is a side view, partly in section, of a bar on completion of the wrapping.

Figure 3 is an end view of the subject of Figure 2.

Figure 4 is a side view, partly in section, after molding of the insulating wrapping to the bar.

Figure 5 is an end view of the subject of Figure 4.

Figure 6 is a side view, partly in section, of completed contact bar.

Figure 7 is a sectional view on line 7—7, Figure 6.

The contact bar according to this invention, shown in Figures 6 and 7, comprises a metal bar

2

A, of steel or any desired suitable metal, and square in cross-section, though the bar may have any suitable cross section, as, for example, circular, triangular, hexagonal, octagonal, or the like.

5 The bar A will be of suitable length for mounting in a circuit breaker and to carry the desired contacts (not shown).

Molded to the bar A, or otherwise closely conformed to the faces thereof, is an insulating material B, which may be a paper or fabric impregnated with a synthetic resin having insulating capacity, as, for example, a phenol formaldehyde type resin, and which may be applied by wrapping.

10 The insulating material, which is continuous, extends substantially beyond the ends of the bar A and is formed with a circular bore e of less diameter than the bar so that it extends inwardly over the ends to engage the end faces of the bar A in areas x, thereby providing abutments for the ends and positively preventing endwise movement of the bar A in the insulating material. The outer surface of the insulating material beyond the ends of bar A forms an extension of the surface 15 of the portion conformed to the bar.

20 The end portions b of the insulating material beyond the ends of the bar A may be plugged with insulating material or a disc of insulating material may be secured within the end portions 25 b to prevent leakage of current to the ends of the bar A from a contact carried by the bar.

20 The method according to this invention, for the production of contact bars of the structure described, will be made apparent by reference to 35 Figures 1—5.

A plurality of approximately square metal bars A, bored and tapped at their ends, as at a, a, are assembled together, as shown in Figure 1, by means of circular rods c provided with reduced 40 threaded ends d, d for engagement in the tapped ends a of the bars A.

The circular rods c will be of such a diameter that no portion of the peripheries of the rods at the end portions thereof will extend beyond any 45 portion of the end faces of the bar, but the end faces of the corners of the bar A will extend beyond the peripheries of the rods. If the bar A is circular, the rod c will be of less diameter than the bar.

50 A plurality of bars A having been assembled together, the assembly is mounted in any suitable mechanism, for rotation as a mandrel, and sheets of insulating material B are wound upon the several bars A.

55 The sheets of insulating material B, as has been

indicated, may be composed of any suitable material, as, for example, paper or fabric impregnated with a synthetic resin, as, for example, a phenol-formaldehyde resin.

The sheets of insulating material B, will, as shown in Figure 1, be of a width greater than the length of the bars A, so that when the sheets are wrapped upon the bars the wrapping will extend beyond the ends of the bars over a portion of the circular rods c.

The wrapping having been completed, the wrapped bars A will appear as shown in Figures 2 and 3, from an inspection of which it will be noted that the insulating material B will conform to the faces of the bars throughout their length and will extend beyond the ends of the bars over the rods c, being in contact therewith only along lines where the diameter of the rods equals the diameters of the ends of the bars A.

The wrapped assembly is now placed in a mold conforming to the contour of the bars A and rods c and heat and pressure applied to compress and conform the insulating material B to the bars A and rods c and to set the resin.

As shown in Figures 4 and 5, the pressure applied in the mold compresses the insulating material and conforms it to the faces of the bars A and, at the same time, conforms it to the circular rods c. The portions of the insulating material conformed to the rods c are somewhat less dense than that conformed to the faces of the bars. However, such portions provide abutments located diagonally of the ends of the bars and engaging those portions of the ends of the bars extending beyond the periphery of the rods, as shown at x, Figure 5.

When the molding is completed, the assembly is removed from the mold and finally the several insulated contact bars are unscrewed from the several rods c, which are then available for the assembly of further bars to be wrapped.

It will be appreciated that various modifications in the particular structure and procedure described may be made without departing from my invention or from the scope of the appended claims.

What I claim and desire to protect by Letters Patent is:

1. The method of producing a contact connector bar having an insulating covering over its entire length and having portions in contact with the ends of the bar forming abutments for the end faces of the bar, comprising assembling a rod with each end of the bar of a diameter such that no portion of the peripheries of the rods at the end portions thereof will extend beyond any portion of the periphery of the bar at the end faces of the bar, but portions of the end faces of the bar will extend beyond the peripheries of the rods, wrapping insulating material over the bar and beyond the ends thereof and over portions of the rods extending from the bar, then subjecting the wrapped assembly to pressure to conform the insulating material to the entire length of the periphery of the bar and to the wrapped portions of the rods and into contact with the end faces of the bar extending from the peripheries of the rods to the periphery of the bar, and then removing the rods from the bar so that an opening of the diameter of the rod is formed in each portion of the insulating material extending from the end faces of the bar to the ends of the insulating material.

2. The method of covering a contact connector

bar having a plurality of similar plane longitudinal faces with an insulating covering over its entire length and having portions in contact with portions of the end faces of the bar forming

5 abutments for the end faces of the bar, comprising assembling a rod with each end of the bar of a diameter such that no portion of the peripheries of the rods at the end portions thereof will extend beyond any portion of the end faces of the bar but portions of the end faces of the bar will extend beyond the peripheries of portions of the rods extending from the bar, wrapping insulating material over the bar and beyond the ends thereof over portions of the rods extending therefrom, then subjecting the wrapped assembly to pressure to conform the insulating material to the entire length of the bar and to the wrapped portions of the rods and into contact with the end faces of the portions of the bar extending from the peripheries of the rods, and then removing the rods from the bar so that an opening of the diameter of the rod is formed in each portion of the insulating material extending from the end faces of the bar to the ends of the insulating material.

20 3. The method of simultaneously covering a plurality of contact connector bars of square cross-section with insulation extending over the entire length of the bars and in engagement with the corner portions of the end faces thereof to form abutments for the ends of the bars, comprising assembling in axial relation a plurality of bars and a plurality of rods with a rod between adjacent bars and a rod extending from the outer 25 end of each end bar, the diameters of the end portions of the rods extending from the bars being such that no portion of the peripheries of the rods at the end portions extend beyond any portion of the end faces of the bars, but the end faces of at least the corners of the bars extend beyond the peripheries of the end portions of the rods, then simultaneously wrapping a sheet of insulating material, including phenol-formaldehyde resin of greater width than the length of the bars on each bar and portions of the rods extending therefrom, subjecting the wrapped assembly to heat and pressure to set the resin and to conform the insulating material to the entire length of the bars and to the portions of the rods and into contact with the end faces of the bars extending from the peripheries of the portions of the rods extending from the ends of the bars and thereafter removing the rods from the bars so that an opening of the diameter of the rod is formed in each portion of the insulating material extending from the end faces of a bar to the ends of the insulating material.
